G. H. FORSYTH

BOLT MOUNTING

Filed July 21, 1924
FIG. 1

FIG. 2

INVENTOR:
GEORGE H. FORSYTH
BY *Cromwell, Freist, Warden*
ATTYS.

UNITED STATES PATENT OFFICE.

GEORGE H. FORSYTH, OF CHICAGO, ILLINOIS, ASSIGNOR, BY MESNE ASSIGNMENTS, TO THE ADAMS & WESTLAKE COMPANY, OF CHICAGO, ILLINOIS, A CORPORATION OF ILLINOIS.

BOLT MOUNTING.

Application filed July 21, 1924. Serial No. 727,401.

This invention relates to bolt mountings such as are adapted for association with the frames of sashes, screens and the like, for the purpose of holding the frames in elevated positions of adjustment.

The primary object of the invention is to provide an improved bolt mounting wherein the component portions are contained within a marginal member of the associated frame and may be readily inserted into or removed from the member upon the withdrawal of an exteriorly accessible positioning element.

Other objects and advantages not herein specifically referred to will be appreciated upon an understanding of the novel features which characterize the construction, arrangement and operation of the bolt mounting.

In order that the invention may be readily understood, one exemplifying embodiment of the same is set forth in the accompanying drawing and in the following detailed description based thereon. Obviously the invention is susceptible of embodiment in other slightly modified forms, and the particular embodiment presented is accordingly not intended to restrict the spirit of the invention short of its intended scope as defined by the appended claims.

In the drawing—

Fig. 1 is a view of a corner of a screen with which the bolt mounting of the invention is associated; and

Fig. 2 is a vertical section on the line 2—2 of Fig. 1.

It will be observed in the drawing that the bolt mounting is contained within a tubular frame member 10 of the screen or other object with which associated, and comprises a guide 11 which is positioned within the member 10, a bolt 12 which is slidably mounted in the guide, a spring 13 which is interposed between the rear end of the bolt and the rear end of the guide, a lever 14 which engages with the bolt, and a screw-pin 15 which fulcrums the lever.

The guide 11 is a rectangular tube which is provided at its rear end with a reduced aperture 16 through which a reduced extension 17 of the bolt carrying the spring 13 slides. The guide is positioned against the outer wall 18 of the frame member with its front end opening to the adjacent end 19 of the same, and is spaced from the inner

wall 19 of the frame member by a channeled reinforcement 20.

The bolt 12 is a rectangular rod which is provided at its rear end with the previously described extension 17, at its front end with a beveled latching portion 21, and intermediate its ends with a transverse slot 22 presenting an abutment 23 against which one end of the lever 14 engages.

The lever 14 is provided at its upper end with a curved head 24 for lateral engagement with the abutment 23 of the bolt, at its lower end with a curved handle 25 for manipulating the bolt and intermediate its ends with a bearing portion 26 for reception of the screw-pin 15. The lever is positioned in a transverse passageway which leads from the inner wall of the frame member to the guideway presented by the guide, and is formed by substantially aligned slots 27 in the frame member, the reinforcement 20 and the guide.

The screw-pin 15 is threaded into an aperture 28 extending through both the side of the frame member and a web of the reinforcement, and is provided interiorly of the frame member with a cylindrical portion 29 on which the lever fulcrums.

When the bolt is in the projected position shown in Fig. 1, the lever is in engagement with the rear end of the slot 27 in the frame member and holds the bolt against further spring-pressed movement from the guide. To disassemble the bolt mounting, the screw-pin is first unscrewed from the frame member, the lever is then withdrawn from its passageway and the bolt is then withdrawn from its guideway. To assemble the bolt mounting, the bolt is first inserted, the lever is then inserted, and the pin is then screwed into the frame member.

When assembled in the manner described, the component portions of the bolt mounting are positively held in operative relation to each other, and present a compact arrangement which is particularly adaptable for use in association with the necessarily narrow frame members of sashes, screens and the like.

I claim:

1. In a bolt mounting, a tubular frame member, a tubular guide positioned in the frame member and provided at its rear end with a constricted aperture, a bolt slidably mounted in the guide and provided interme-

- diate its ends with a transverse shoulder and at its rear end with a reduced extension slidably mounted in the aperture, a helical spring encompassing the extension and acting between the rear end of the guide and the rear end of the bolt to project the front end of the bolt from the guide, a lever passing through slots in one wall of the frame member and the guide and provided interiorly of the frame member with an end portion for lateral engagement with the bolt and exteriorly of the frame member with a handle for oscillating the lever to operate the bolt, and an exteriorly accessible pin 65
removably mounted in another wall of the frame in perpendicular relation to the lever for fulcruming an intermediate portion of the lever, said bolt, spring and lever being removable upon extraction of the pin.
2. In a bolt mounting, a tubular frame member, a tubular guide positioned in the frame member against the outer wall of the same and provided at its rear end with a constricted aperture, a reinforcement positioned in the frame member between the inner wall of the same and the guide, a bolt slidably mounted in the guide and provided intermediate its ends with a transverse shoulder and at its rear end with a reduced extension slidably mounted in the aperture, a helical spring encompassing the extension and acting between the rear end of the guide and the rear end of the bolt to project the front end of the bolt from the guide, a lever passing through slots in the inner wall of the frame member the reinforcement and the guide and provided interiorly of the frame member with a convex end portion for lateral engagement with the bolt and exteriorly of the frame member with a curved handle for oscillating the lever to operate the bolt, and a screw-pin removably mounted in the frame and provided interiorly of the same with a cylindrical end portion for fulcruming an intermediate portion of the lever. 10
3. In a bolt mounting, a frame member having a longitudinally extending guideway, a bolt slidably mounted in the guideway, a spring tending to press the bolt from the guideway, a lever provided at one end with a portion for engagement with the bolt and at the other end with a handle for oscillating the lever to retract the bolt in the guideway against the action of the spring, and an exteriorly accessible pin screwed into one wall of the frame member and having a journalling portion in perpendicular relation to the lever for fulcruming engagement with an intermediate portion of the same, said bolt, spring and lever being removable upon extraction of the pin. 15
4. In a bolt mounting, a narrow tubular frame member, an elongated tubular guide positioned within the frame member adjacent one of the narrower walls thereof, an elongated reinforcement also positioned within the frame member between the guide and the other narrow wall of the frame member, a bolt slidably mounted in the guide and provided intermediate its ends with a transverse shoulder, a spring also mounted in the guide at the rear end of the bolt for projecting the front end of the bolt from the guide, a lever passing through slots in one of the narrower walls of the frame member, the reinforcement and the guide and provided interiorly of the frame member with an end portion for engagement with the shoulder of the bolt and exteriorly of the frame member with a handle for oscillating the lever to retract the bolt in the guide against the action of the spring, and an exteriorly accessible screw in screw-threaded engagement with one of the wider walls of the frame member and provided interiorly of the same with a cylindrical end portion in perpendicular relation to the lever for fulcruming an intermediate portion of the same. 20
5. In a bolt mounting a hollow sheet metal sash member, a bolt positioned within and slidable longitudinally of the sash member, a spring also positioned within the sash member in engagement with one end of the bolt for projecting the other end from the sash member, a lever provided at one end with a portion for engagement with the bolt between the projecting and spring engaging ends of the same and provided at the other end with a handle for oscillating the lever to retract the bolt in the sash member against the action of the spring, and an exteriorly accessible pin screwed into one wall of the sash member and having a journalling portion in perpendicular relation to the lever for fulcruming engagement with an intermediate portion of the same, said bolt, spring and lever being removable upon extraction of the pin. 25
6. In a bolt mounting, a hollow sheet metal sash member, a locking element positioned within the sash member, a lock-operating element operatively connected with the locking element, and an exteriorly accessible pin screwed into one wall of the sash member and having a plain cylindrical journalling portion at one end of the threaded portion in perpendicular relation to the lock-operating element for fulcruming engagement with an intermediate portion of the same, said locking element and lock-operating element being removable upon extraction of the pin. 30

In testimony whereof I have hereunto subscribed my name.

GEORGE H. FORSYTH.
